(57) CLAIM

The ornamental design for a file as shown and described.

DESCRIPTION

FIG. 1 is a front elevation view of a file showing my new design;

FIG. 2 is a rear elevation view thereof;

FIG. 3 is a top plan view thereof, a bottom plan view being a mirror image of the top plan view;

FIG. 4 is a right side elevation view thereof;

FIG. 5 is a left side elevation view thereof;

FIG. 6 is a sectional view thereof taken along line 6-6 in FIG. 1;

FIG. 7 is an enlarged sectional view thereof taken at line 7 shown in FIG. 6;

FIG. 8 is a perspective view thereof; and,

FIG. 9 is a perspective view thereof in a state wherein a stopper portion is released.

The evenly spaced broken lines depict environment and form no part of claimed design. The dot-dash broken lines depict the bounds of the cross-section views and form no part of the claimed design.

1 Claim, 9 Drawing Sheets
